SHUTTLE POSITION DETECTOR FOR WEFT REPLENISHING LOOMS

Clifford Darwin, Worcester, Mass., assignor to Crompton & Knowles Loom Works, Worcester, Mass., a corporation of Massachusetts

Application January 27, 1941, Serial No. 376,044

10 Claims. (Cl. 139—341)

This invention relates to improvements in shuttle position detectors for weft replenishing looms and it is the general object of the invention to provide such a detector so constructed as to move to detecting position along a path which is behind the front of the shuttle box.

In the usual weft replenishing loom it is necessary to revoke transfer if the shuttle is improperly positioned to receive a reserve bobbin on a replenishing beat of the loom. This result is usually accomplished by a so-called shuttle feeler which is moved across the shuttle path preparatory to transfer and has connections with the transerrer mechanism acting to prevent operation of the latter when a misplaced shuttle engages the shuttle feeler. Heretofore these shuttle feelers have been so mounted as to move either downwardly to a position in front of the path of the shuttle or rearwardly to a position behind the front wall of the shuttle. Since it is necessary that the shuttle feeler be close to a properly boxed shuttle it has been necessary to use a short binder at the magazine end of the loom to avoid interference with the shuttle feeler.

It is an important object of my present invention to provide a shuttle feeler which shall move to detecting position along a path located within the path of flight of the shuttle or between the front and back walls of the shuttle box so that a longer binder may be used at the magazine end of the lay. In the description to follow the shuttle feeler is moved downwardly from a normally raised position.

In the usual drop box loom the box front binder will extend a considerable distance beyond the inner tip of a properly boxed shuttle, thereby providing a binder of considerable length affording better checking conditions than those existing at the magazine end of the loom. In automatic pick and pick filling mixing looms it is customary to employ shifting shuttle boxes at the magazine end of the lay, and these shuttle boxes are of the same general construction as those located at the opposite end, that is, they carry shuttle binders which extend to a point nearer the adjacent selvage than does the inner tip of a properly boxed shuttle. On this type of loom the ordinary shuttle feeler cannot be used and it is a further purpose of my present invention to provide a shuttle feeler which can be moved preferably downwardly into a shuttle box along a path behind the binder and the forward part of the shuttle box.

The particular change in loom operation which I effect when the shuttle is misplaced is loom

stoppage. This stoppage of the loom is effected by connections from the shipping mechanism to a shuttle feeler which will have a normal stroke to permit continued loom operation if the shuttle is properly positioned but which will have an interrupted or abnormal stroke should the shuttle be misplaced and thereby stop the loom.

It is a further object of my present invention to provide the shuttle feeler in the form of a lever which floats on and derives its actuating force from the transerrer arm during a replenishing operation of the loom.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is an end elevation of a portion of a portion of a loom having a magazine made according to my present invention, the shuttle boxes being shown in section and the transerrer and shuttle feeler being shown in normal raised position in full lines and in their lowest position in dotted lines,

Fig. 2 is a view similar to Fig. 1 on a smaller scale showing a shipping mechanism of a loom and the shuttle feeler engaging a misplaced shuttle to cause loom stoppage,

Fig. 3 is a plan view of the shuttle box taken in the direction of arrow 3, Fig. 2, parts being omitted,

Fig. 4 is a detailed front elevation taken in the direction of arrow 4, Fig. 2, and

Fig. 5 is a diagrammatic view showing the relation between the paths of the front and back walls of the shuttle box during a forward beat of the lay, together with the path of the shuttle feeler.

Referring to the drawings, I have shown a loom frame 10 having mounted thereon a magazine M which may be of the multicolor type and including in its construction a transerrer arm 11 pivoted as at 12 to the magazine and having a bobbin engaging heel 13. The transerrer arm ordinarily lies between the cloth and the inner plate 14 of the magazine and has depending arms 15 to which is pivoted a transerrer latch 16 movable forwardly on replenishing beats of the loom by a bunter 17 carried by the gang of shuttle boxes G. The usual comparatively heavy torsion spring 18 serves to hold the transerrer arm normally raised and in engagement with part of plate 14, as shown in full lines in Fig. 1.

The latch is ordinarily down as indicated in dot and dash lines in Fig. 1, but is raised by a rod 19 operating in the usual manner preparatory to transfer.

The gang of boxes G are shown in the present instance as including four cells 20, 22, 23 and 24 the first two of which may if desired be used for mixing filling in a loom having a group of weaving shuttles each remaining active for but one pick at a time and being received at regular intervals and in rotation by the shuttle box 20. The boxes shift in a four-pick cycle, being up for two picks and then down for two picks. The shifting may be effected through a box rod 25 and the magazine will be located high enough so that the shuttle S in the top box 20 can be replenished when the shuttle boxes are raised. The lower boxes may be provided with a bobbin guide 26 for the outgoing bobbins.

Referring particularly to Fig. 3 the lay L of the loom is provided with inner and outer box guides 30 and 31, respectively, by which the gang G is guided. The top cell is provided with an overhanging shelf 32 which extends forwardly from a back wall 33 to a box front 34 from which extends forwardly a series of vertically spaced lugs 35, one of which is shown in Fig. 3, to receive a binder pivot pin 36. Cells 20 and 22 are provided each with a shuttle binder 37 pivoted as at 38 to the right end of the gang G as viewed in Fig. 3 and urged rearwardly by a binder spring 39. As seen in Fig. 3 the binder has the inner or left end thereof extended to a point between the tip T of the shuttle S and the cloth not shown but to the left of Fig. 3.

The mechanism thus far described operates in the usual manner, a weft detector not shown calling for a replenishing operation and causing elevation of rod 19 to lift the latch 16 into the path of the bunter 17 when the gang G is in high position. As the lay moves forwardly from the full to the dotted position shown in Fig. 1 the transerrer arm is rocked about its pivot 12 and moves downwardly to insert a reserve bobbin B into the shuttle S during the latter part of the forward motion of the lay. As the lay recedes the spring 18 lifts the transerrer arm and moves the latch rearwardly. The bunter 17 eventually leaves the latch and the latter is free to drop to its non-transferring position, rod 19 having previously been lowered by the usual mechanism. My invention is not necessarily limited to use with a multi-color magazine, but when such a replenishing mechanism is used it may be of the usual form as shown in Patent No. 1,080,748, and the relationship between the transerrer and the shifting shuttle boxes may be as set forth in co-pending application Serial No. 365,093.

The shipping mechanism is of the usual form and includes a shipper handle 42 mounted on a shipper rod 43 rotatable in the loom frame. A stud 45 on handle 42 enters a notch 46 in a control member 47 and is thus held yieldingly in the running position shown in full lines in Fig. 2. There is also employed a brake handle 48 mounted for oscillating motion on the rod 43 and held yielding in the "off" position shown in full lines, Fig. 2, by a stud 49 on handle 48 which enters a notch 50 in a brake setting mechanism of usual form part of which is indicated at 51. A screw 52 on handle 42 is engaged by lug 53 on the brake handle to move the shipper handle to "off" position whenever the brake is set to stop the loom. It is believed sufficient to state that when

either handle 42 or 48 moves rearwardly or to the dotted line position in Fig. 2 the loom will be disconnected from its driving motor, and when handle 48 is thus moved the brake will be applied. Shipping mechanisms are well known and further description is not thought necessary. An example of shipping mechanism which may be used in connection with my present invention is shown in my co-pending application Serial No. 359,568.

In carrying my invention into effect I provide a shuttle position detector or feeler 55 comprising a floating lever pivoted as at 56 to the transerrer arm 11. The rear or right end of the shuttle feeler as seen in Fig. 1 is formed with a downwardly extending shuttle detecting foot 57, while the left end 58 is held yieldingly against the stop 59 held in vertically adjusted position on the magazine frame as indicated at 60, Fig. 1. A light tension spring 61 connected to the stop 59 is attached at 62 to the shuttle feeler between the pivot 56 and that part of end 58 which engages the stop 59. The spring therefore holds the forward or left end 58 of the shuttle feeler yieldingly against the stop 59.

Pivoted to end 58 of the shuttle feeler at 64 is a depending rod 65 which passes through a lug 66 formed on a knock-off dagger 67 pivoted on an extension 68 of stud 49 on brake handle 48. As shown in Fig. 1 the left end of the dagger is provided with an adjustable stop screw 69 engageable with arm 44 of handle 48 to limit downward motion of the right end of the dagger relatively to the brake handle. The dagger is notched as at 70 to receive a bunter 71 secured as at 72 to the lay. Upper and lower collars 73 and 74, respectively, are adjustable vertically on rod 65 and a compression spring 75 is located between lug 66 and collar 73. The dagger is normally supported by collar 74 to locate the notch 70 above the path of the bunter 71 when rod 65 is held up in normal position by spring 61.

The top shelf 32 of the upper box cell 20 is provided with a transverse slot 80 slightly wider than the foot 57 and extending from the back 33 of the boxes forwardly to the box front 34 from which the box mouth 81 extends.

In operation, the transerrer arm and the shuttle feeler will normally be in the full line position indicated in Fig. 1. The shuttles are picked in rotation and enter box 20 to be raised to transfer position at regular intervals, whether or not replenishment is necessary. When transfer occurs as already described the pivot 56 will descend and spring 61 will hold the forward end 58 of the shuttle feeler up against stop 59, thus causing foot 57 to descend and pass through slot 80 into top cell 20 behind front wall 34. If the shuttle is properly positioned the foot 57 will pass below the shuttle tip to a point close to the bottom of cell 20, reaching its lowest position as the transerrer arm completes its descent upon arrival of the lay at front center position. Under these conditions stop 59 becomes a fixed pivot around which the shuttle feeler turns and rod 65 will remain in raised position to hold dagger 67 above the advancing bunter 71. The latter will therefore move forwardly without entering notch 70 and the loom will continue to run.

If, on the other hand, the shuttle is improperly positioned and projects inwardly from its normal position sufficiently to lie within the path of the foot 57, the latter will engage the shuttle during descent of the transerrer arm at a point which becomes a temporary pivot around which the

shuttle feeler will move in a counter-clockwise direction as viewed in Fig. 2. During continued downward motion of the transerrer arm end 58 of the floating lever will be lowered against the action of spring 61. The resultant lowering of rod 65 places the dagger 67 in the path of the bunter 71 and further downward motion of the dagger is prevented by engagement of the stop screw 69 with arm 44. The advancing bunter thereupon enters notch 70 and continued forward motion of the lay will swing the handle 48 rearwardly, thereby disconnecting the driving mechanism from the loom and applying the brake.

After the dagger 67 is engaged by the bunter 71 the transerrer arm continues to move downwardly and cause further descent of the rod 65, which, however, merely compresses spring 75 without disturbing the relationship of bunter 71 and the dagger, since spring 75 is too weak to unseat the bunter 71 from the notch 70.

The lay will continue to move a short distance after the brake is applied, depending upon the effectiveness of the brake, and may start rearwardly, but will ordinarily be stopped prior to top center or picking position. During this backward motion of the lay the transerrer arm rises under action of spring 18 and the pivot 64 will move upwardly by the action of spring 61 until end 58 engages stop 59, after which further upward motion of the transerrer arm will restore the shuttle feeler to its normal raised position. The shipper handle will remain in forward position and dagger 67 will be released by rearward motion of bunter 71 with the lay, and for this reason rod 65 can rise with collar 74 in engagement with lug 66. After the loom has been stopped the weaver will correct the defective transfer and replenish the shuttle by hand and will then pull the shipper handle forwardly the effect of which is to move the dagger 67 to its normal rear position above the bunter 71.

It is to be understood that if the foot 57 engages the top of a widely misplaced shuttle the effect is to give the pivot 64 a relatively large downward motion and spring 75 is made sufficiently long to accommodate this motion. If, on the other hand, the shuttle is only slightly misplaced the foot will move to a lower position in its path before having its motion interrupted and the downward motion of pivot 64 will be relatively less. The parts are proportioned to give a satisfactory indication to stop when the minimum down motion of pivot 64 occurs.

Any usual form of thread cutter as well as resetting mechanism for the magazine may be employed in addition to the shuttle feeler set forth herein.

In Fig. 5 I have illustrated diagrammatically the relation between the foot 57 and the front and back walls of the shuttle box immediately preceding and following the front center position of the lay. The term "box front" is used herein to include any part of the box structure, such as wall 34 or binder 37, which is in front of the shuttle and adjacent to the shuttle feeler. In Fig. 5 the location of the breast beam of the loom is indicated by the line F and the vertical ordinates along this line represent the angular position of the lay, the points o, a and b representing the lay at bottom, front and top center positions, respectively. The large left hand curve BF indicates the distance of the box front from the breast beam for different angular positions of the lay, and line BB gives corresponding values

for the box back. The horizontal distance between lines BF and BB is proportional to the distance between the front and back walls of the shuttle box. The changing locations of this distance or dimension as the lay moves first forwardly and then backwardly generates a zone Y within which the foot 57 must be confined when it is below the box front.

It may be assumed that during the descent of the transerrer arm the front of foot 57 will reach the level of the top of the box front at point K on line ox while the lay is moving forwardly. The box front will be at point m on line BF and the line ng representing the length of foot 57 will lie within zone Y. If the shuttle is properly positioned the foot 57 will thereafter swing along an arc which lies below a horizontal line passing through the pivot 56 and the foot will therefore move forwardly as it moves downwardly behind the box front, as indicated by the curve ns. The back end of the foot will correspondingly move along a curve qt and be in front of the box back. When the lay is on front center position foot 57 will have reached its lowest and also its most forward position as indicated by the points s and t, and as the lay recedes the foot will rise and will emerge from zone Y at line pr along a path having a rear component.

If the shuttle is misplaced it will engage foot 57 at any one of a number of points the lowest of which, near the shuttle point, is indicated at u. Thereafter center 56 continues to descend and causes a slight rearward motion of foot 57 indicated by curved dotted line uw, Fig. 5. The corresponding curve lf bows rearwardly but does not touch line BB, remaining in zone Y. As the lay recedes the foot 57 moves forwardly until end 58 engages stop 59, and then moves rearwardly as in the previously described instance. The whole range of detecting movements of foot 57 are therefore located between the front and back walls of the shuttle box and there is no interference. The point u occurs early enough in the advance of the lay to allow time for stopping the loom. The region of activity of the foot 57 is kept as near the box front as convenient to afford a leverage favorable to the quick operation of the dagger 67.

From the foregoing it will be seen that I have provided a shuttle position detector which moves along a path behind the front wall of the shuttle, thereby permitting the use of a long binder at the magazine end of the loom. It will also be seen that I have provided a floating lever deriving its operating force from the transerrer arm and so controlled as to operate around two different centers one of which is the point of contact with a misplaced shuttle and the other of which is stop 59 which is operative at the start of a detecting stroke to cause the shuttle feeler to move toward detecting position. It will further be seen that provision is made for permitting the transfer to take place even though the shuttle be misplaced and then stop the loom prior to picking to prevent damage to the warp shed. It will further be noted that provision is made for permitting engagement between the bunter 71 and the latch 67 whether the foot 57 engages a shuttle which is only slightly misplaced or widely misplaced, and that provision is made for continued motion of the transerrer arm after the stopping stroke has been initiated.

Having thus described my invention it will be seen that changes and modifications may be made therein by those skilled in the art without

departing from the spirit and scope of the invention and I do not wish to be limited to the details herein disclosed, but what I claim is:

1. In a weft replenishing loom having a lay along which travels a shuttle from the front wall of which a weft thread extends to the adjacent selvage, loom stopping mechanism normally in running position, a shuttle position detector normally out of the path of the shuttle, means tending to cause said shuttle position detector to have a complete detecting stroke behind said weft thread and toward the path of the shuttle during a replenishing beat of the loom, the shuttle when positioned on a replenishing beat to engage the shuttle position detector acting to interrupt said detecting stroke, and means controlled by the shuttle position detector to cause the stopping mechanism to move to stopping position when the detecting stroke of the shuttle position detector is interrupted by a misplaced shuttle.

2. In a weft replenishing loom having a shuttle to be replenished with a reserve bobbin, a transferrer arm having a working stroke on the replenishing beat of the loom to move the bobbin toward the shuttle, a shuttle position detector connected to the transferrer arm to be moved thereby on a working stroke thereof and capable of having either a normal stroke or an abnormal stopping stroke, means cooperating with the transferrer arm to cause the shuttle position detector to have a normal stroke when the shuttle is properly positioned for replenishment, and the shuttle when positioned to engage the shuttle position detector on replenishing beats cooperating with the transferrer arm to give the shuttle position detector an abnormal stopping stroke, and means controlled by the shuttle position detector to stop the loom when said shuttle position detector has an abnormal stopping stroke.

3. In a weft replenishing loom having a shuttle to be replenished with a reserve bobbin, a transferrer arm having a working stroke on the replenishing beat of the loom to move the bobbin toward the shuttle, a shuttle position detector pivoted intermediate its ends to the transferrer arm to be given a downward motion toward the shuttle when the transferrer arm has a working stroke, one end of the shuttle position detector capable during a working stroke of the transferrer arm of having either a full normal stroke when the shuttle is properly positioned for transfer and out of the path of the shuttle position detector or an interrupted shorter stroke when the shuttle is improperly positioned for transfer and extends into the path of said one end of the shuttle position detector, means to hold the other end of said shuttle position detector stationary when the first named end has a full normal stroke, said other end of the shuttle position detector moving against the action of said means when the first named end has an interrupted stroke, and means controlled by said other end to stop the loom when the shuttle position detector has an interrupted stroke and said other end is moved against the action of said means.

4. In a weft replenishing loom having stopping mechanism to be moved from running to stopping position to stop the loom and having a lay provided with a shuttle box containing a shuttle to be replenished during forward motion of the lay on a replenishing beat of the loom by downward motion of a transferrer arm which is normally in raised position, a shuttle position detector comprising a floating lever, a pivotal connection between the lever and the transferrer

arm to cause the lever to move downwardly when the transferrer arm descends, a controller for the stopping mechanism connected to the lever and normally located in non-stopping position, said lever having a portion moving downwardly to detect the position of the shuttle along the length of the lay with a normal stroke when the shuttle is properly positioned for replenishment and the transferrer arm descends, and said portion of the lever engaging a misplaced shuttle to have downward motion thereof arrested during descent of the transferrer arm and the latter thereupon causing movement of that part of the lever connected to the controller to move the latter to stopping position.

5. In a weft replenishing loom having a lay along which a shuttle travels in a given path toward transfer position and in which a weft thread extends from the front wall of the shuttle to the adjacent selvage, stopping mechanism for the loom normally in running position, a shuttle position detector normally above the path of the shuttle, means to cause the shuttle position detector to have a downward motion during a weft replenishing operation of the loom across said shuttle path at a point between the selvage and a properly positioned shuttle and behind said weft thread, the shuttle when positioned to engage the shuttle position detector during a replenishing operation interrupting said downward motion of the shuttle position detector; and an element connected to said stopping mechanism and said shuttle position detector to be positioned by the latter in the path of the lay to cause the latter to move the stopping mechanism from running to stopping position when downward motion of the shuttle position detector is interrupted by the shuttle during a weft replenishing operation of the loom.

6. In a weft replenishing loom having a shuttle to be replenished with a reserve bobbin, a transferrer arm having a working stroke on replenishing beats of the loom to move the bobbin toward the shuttle, a shuttle position detector, means to transmit a force from the transferrer arm during a working stroke thereof to the shuttle position detector to move the latter toward the shuttle, said shuttle position detector having two spaced portions each capable of a downward motion, means to hold one of said portions substantially stationary to cause movement of the other portion by the transferrer arm on a working stroke of the latter across the path of the shuttle when the latter is properly positioned for transfer on a replenishing beat of the loom, the shuttle when located in the path of said other portion on a replenishing beat of the loom engaging said other portion and cooperating with the transferrer arm to move the first named portion downwardly, and means controlled by said first named portion when the latter moves downwardly to effect loom stoppage.

7. In a weft replenishing loom having a shuttle movable along a given path to a position to be replenished with a reserve bobbin, a transferrer arm having a working stroke on weft replenishing beats of the loom to move the reserve bobbin toward the shuttle, a shuttle position detector having one portion movable toward the shuttle path, resilient means acting on another portion of the shuttle position detector tending to prevent movement of said other portion but yieldable to permit movement of said other portion, means to connect the transferrer arm to the shuttle position detector at a point between said

portions and transmit a force derived from the transerrer arm when the latter has a working stroke to the shuttle position detector and cooperating with said resilient means to give said one portion a normal motion along a given detecting path which crosses the shuttle path when the shuttle is properly placed for replenishment, the shuttle when extending into said detecting path on a weft replenishing beat of the loom engaging said one portion to cause the transerrer arm on a working stroke thereof to give the shuttle position detector an abnormal movement and cause said other portion to have a stopping movement against the action of said resilient means, loom stopping mechanism, and means controlled by said other portion when the latter has a stopping movement to cause said stopping mechanism to stop the loom.

8. In a weft replenishing loom having a shuttle to be replenished by a reserve bobbin when the shuttle is in transfer position, a transerrer arm having a working stroke to move the reserve bobbin toward the shuttle on weft replenishing beats of the loom, a shuttle position detector connected to the transerrer arm to be given a shuttle position detecting stroke on replenishing beats of the loom by a force derived from the transerrer arm when the latter has a working stroke, means additional to and cooperating with the transerrer arm to cause the shuttle position detector to have a normal detecting stroke when the shuttle is in proper transfer position, the shuttle when extending into the path of the shuttle position detector on a working stroke of the transerrer arm engaging and interrupting the normal detecting stroke of the shuttle position detector to cause the latter to have an abnormal stroke against the action of said means, and loom stopping mechanism controlled by the shuttle position detector to stop the loom when said shuttle position detector has an abnormal stroke.

9. In a weft replenishing loom having a shuttle to be replenished with a reserve bobbin, a transerrer arm having a transferring stroke on replenishing beats of the loom, a shuttle position detector having a portion thereof to receive an actuating force from the transerrer arm when

- the latter has a transferring stroke, said shuttle position detector capable of having either of two characters of motion when receiving the actuator force, one motion being normal and the other 5 motion being abnormal to effect loom stoppage, loom stopping mechanism, a controller for the latter normally in running position and movable to stopping position by the shuttle position detector when the latter has an abnormal motion 10 to cause operation of the stopping mechanism, and means additional to the transerrer arm connected to the shuttle position detector to cause the latter to have a normal motion when receiving said actuating force from the transerrer arm on a replenishing beat of the loom, provided the shuttle is properly positioned for replenishment, the shuttle when positioned to 15 engage the shuttle position detector on a replenishing beat of the loom cooperating with the transerrer arm to give the shuttle position detector an abnormal motion against the action of said means to move the controller to stopping position and cause the stopping mechanism to stop the loom.
- 20 25 10. In a weft replenishing loom having a shuttle to be replenished with a reserve bobbin, a transerrer arm having a working stroke on the replenishing beat of the loom to move the bobbin toward the shuttle, a shuttle position detector 30 pivoted to the transerrer arm and movable by the latter toward the shuttle on a replenishing beat of the loom, resilient means connected to the shuttle position detector and cooperating with the transerrer arm to cause said detector to 35 have a normal stroke when the shuttle is properly positioned for replenishment and out of the path of movement of the shuttle position detector during a working stroke of the transerrer arm on a replenishing beat of the loom, the shuttle when positioned to engage the shuttle position detector on a replenishing beat cooperating with the transerrer arm to give the shuttle position detector an abnormal stopping stroke against the action of said resilient means, and controlled 40 45 by the shuttle position detector to stop the loom when the shuttle position detector has an abnormal stopping stroke.

CLIFFORD DARWIN.
